DEVICE FOR MOUNTING ROLL CHOCKS

Will A. Breedon and Louis L. Miller, Cleveland, Ohio, assignors to United States Steel Corporation, a corporation of New Jersey

Application February 13, 1952, Serial No. 271,395

5 Claims. (Cl. 80—55)

This invention relates to improved devices for mounting roll chocks in rolling mill housings.

During rolling operations rolls are subject to severe stresses which tend to deflect them from their normal axes and thus cause their bearings to wear unevenly. To overcome this tendency, roll chocks can be mounted for free pivotal movement on axes perpendicular to the roll axes, whereby the bearings remain in alignment with the rolls as the latter deflect. In modern constructions it is also considered important to make rolls and their chocks axially adjustable.

An object of the present invention is to provide an improved mounting device which both furnishes axial adjustability and also allows the roll chocks to pivot freely on axes perpendicular to the roll axes.

A more specific object is to provide a mounting device which includes a tab fixed to the side of a roll chock and a pair of adjustable jaws which grip the tab and yet allow pivotal movement of the chock.

In accomplishing these and other objects of the invention, we have provided improved details of structure, preferred forms of which are shown in the accompanying drawings, in which:

Figure 1 is a side elevational view of a portion of a rolling mill equipped with a mounting device which embodies features of the present invention;

Figure 2 is a horizontal sectional view taken substantially on line II—II of Figure 1;

Figure 3 is a vertical sectional view taken substantially on line III—III of Figure 1;

Figure 4 is a horizontal sectional view taken substantially on line IV—IV of Figure 3; and

Figure 5 is a fragmentary vertical sectional view similar to Figure 3, but showing a modification.

Figures 1 and 2 show a rolling mill which includes spaced apart housings 10 and 12, upper and lower work rolls 13 and 14 respectively, and upper and lower roll chocks 15 and 16 respectively. The two chocks in the housing 10 can be mounted in any standard or desired way. Preferably the usual shims 17 are included at one side of the chocks in both housings 10 and 12. Mounting devices of the present invention, hereinafter described, are used to mount the two chocks in the housing 12. The housings carry the usual turn-down screws 18, and the rolls and chocks can be removed from the housings by lifting them upwardly in the usual fashion, after moving the turn-down screws and their bearings out of the way.

The mounting device of the present invention is similar on both the upper and lower chocks 15 and 16 and therefore is described in detail only for the upper chock 15. The side of this chock carries a fixed and preferably integral tab 19, the center line of which either coincides with the transverse center line of the roll bearing within the chock or is fairly close thereto. Housing 12 has a transverse opening 20 alongside said tab. An inner jaw 21 is mounted in opening 20 for sliding movement in a direction parallel to the roll axis and carries an integral

2

lug 22 which overlies the outer face of housing 12. An outwardly projecting bolt 23 is fixed to the outer face of housing 12 and extends through an opening in lug 22. Nuts 24 are threadedly engaged with bolt 23 on opposite sides of said lug. The inner jaw has a transverse opening 25, the outer portion of which is screw threaded. An outer jaw 26 has an integral stud 27 slidably received in said opening. A cap screw 28 is threadedly engaged with the threaded portion of this opening and abuts the outer end of stud 27. Preferably this cap screw carries a lock nut 29.

Tab 19 is gripped between jaws 21 and 26. Pressure on the tab is controlled through adjustment of the cap screw 28. The jaws can be loosened for removing the chock and roll from the housing merely by loosening this screw. The axial position of the jaws and also of the tab and chock 15 is controlled by adjustment of nuts 24 on bolt 23. Thus it is seen that the mounting device allows both ready adjustment of the axial position of the roll, as well as ready removal of the roll chock from the housing.

As Figure 3 shows, the gripping faces of both the jaws 21 and 26 are convex, while the faces of the tab are flat. Thus the tab is free to rock on an axis which is situated midway between the grip points and is perpendicular to the roll axis.

The turn-down screw and the housing respectively engage the upper face of the upper chock 15 and the lower face of the lower chock 16 in a way which allows such rocking movement. The upper face of chock 15 carries a freely slidable block 30 which has a concave socket 31 in its upper face (Figures 1 and 3). The lower end of the turn-down screw 18 is convex and is received in said socket. As the upper chock 15 pivots, the block 30 slides back and forth along the upper surface of the chock and at the same time pivots with respect to the turn-down screw. The bottom face of chock 16 carries a fixed shoe 32 whose lower surface is convex (Figure 3). The center about which this surface is constructed preferably coincides with the center line of the tab 19 on this chock, which line also is the center about which the chock pivots. The shoe rests on a flat bearing surface 33. As the lower chock 16 pivots, the shoe 32 slides back and forth across this bearing surface. The axes of the rolls may move upwardly or downwardly depending on whether the rolls are new or dressed down from their original diameter. Therefore, the bearing means of the chocks must allow for different positioning of the chock. The tabs 19 are provided with bearing areas long enough to provide ample contact with the convex jaws 21 and 26 regardless of the positions of the rolls in the roll housing.

Figure 5 shows a modification in which the tab 19a has convex surfaces and the gripping surfaces of the jaws 21a and 26a are flat. The structures are otherwise the same. The chocks can rock in the same fashion as already described for Figures 1 to 4.

From the foregoing description it is seen that the present invention furnishes a roll mounting device of simple construction and yet which permits axial adjustment of the rolls as well as rocking or pivotal movement of the chocks. The device has the further advantage that it is readily installed on existing rolling mills with but minor alterations.

While two embodiments of our invention have been shown and described, it will be apparent that other modifications and adaptations may be made without departing from the scope of the following claims.

We claim:

1. In a rolling mill which includes a housing, a chock mounted in said housing and a roll rotatably mounted in said chock, the combination with said housing and chock of a mounting device which comprises a tab fixed to a

side face of said chock adjacent the horizontal transverse center line of the chock, an inner jaw mounted in said housing for sliding movement in a direction parallel to the roll axis, an outer jaw slidably mounted on said inner jaw, said jaws having faces which engage opposed faces of said tab for gripping the latter within the confines of said housing, means for adjusting said outer jaw with respect to said inner jaw and thereby adjusting the gripping pressure on said tab, and means for adjusting said inner jaw relative to said housing and thereby axially adjusting said chock and said roll, one of the engaging faces of said tab and said jaws located at the inner side of said tab and one located at the outer side thereof being convex and allowing said chock to pivot on an axis perpendicular to the roll axis.

2. In a rolling mill which includes a housing, a chock mounted in said housing and a roll rotatably mounted in said chock, the combination with said housing and chock of a mounting device which comprises a tab fixed to a side face of said chock adjacent the horizontal transverse center line of the chock, an inner jaw mounted in said housing for sliding movement in a direction parallel to the roll axis, screw-threaded means projecting from the outside of said housing and adjustably engaging said inner jaw for positioning the latter, an outer jaw slidably mounted on said inner jaw, and screw-threaded means engaging said inner jaw and abutting said outer jaw for positioning the latter, said jaws having gripping surfaces engaging opposed faces of said tab within the confines of said housing, one of the gripping surfaces located at the inner side of said tab and one located at the outer side thereof being convex and permitting said chock to pivot on an axis perpendicular to the roll axis.

3. In a rolling mill which includes a housing, a chock mounted in said housing, and a roll rotatably mounted in said chock, the combination with said housing and chock

5 of a mounting device which comprises a tab fixed to a side face of said chock with the horizontal transverse center line of the chock extending through the tab, said housing having a horizontal passage extending in a direction parallel to the roll axis and into which said tab projects, an inner jaw mounted in said passage for sliding movement in a direction parallel to the roll axis and having a gripping surface engaging the inner face of said tab, screw-threaded means projecting from the outside of said housing and adjustably engaging said inner jaw for positioning the latter, an outer jaw slidably mounted on said inner jaw and having a gripping surface engaging the outer face of said tab, and screw-threaded means engaging said inner jaw and abutting said outer jaw for positioning the latter, one of the engaging faces of said tab and said jaws located at the inner side of said tab and one located at the outer side thereof being convex enabling said chock to pivot about its horizontal transverse center line.

10 15 20 25 30 35 4. A combination as defined in claim 3 in which the convex faces are on said jaws.

5. A combination as defined in claim 3 in which the convex faces are on said tab.
